CLAIM

The ornamental design for pill/capsule medicine container
having combination cap, cotton padding and interconnecting
flexible cord, as shown and described.

DESCRIPTION

FIG. 1 is a perspective view of a pill/capsule medicine
container having combination cap, cotton padding and inter-
connecting flexible cord showing my new design, with the
cap shown in raised condition;

FIG. 2 is a side elevational view thereof, with the cap shown
in closed condition;

FIG. 3 is a top plan view thereof; and,
FIG. 4 is a bottom plan view thereof.
